UNITED STATES PATENT OFFICE.

JAMES F. BABCOCK, OF BOSTON, MASS., ASSIGNOR TO JOSEPH T. BROWN,
JOSEPH T. BROWN, JR., AND CHARLES H. BASSETT, ALL OF SAME PLACE.

DESIGN FOR A BOTTLE.

SPECIFICATION forming part of Design No. 12,292, dated June 7, 1881.

Application filed April 25, 1881. Term of patent 7 years.

To all whom it may concern:

Be it known that I, JAMES F. BABCOCK, a citizen of the United States, residing in Boston, Massachusetts, have invented or produced 5 a new and original Design for a Bottle, of which the following is a specification.

My design for a bottle is fully shown in the accompanying drawings, Figure 1 being a side view of the bottle, and Fig. 2 a sectional plan 10 on the line 1 2.

The body A of the bottle is of rectangular form, and is contracted at the top B and bottom D. On each corner of the bottle and following the outline of the same is a rounded 15 rib, a, and on each side of the bottle and extending from one corner rib to the other are four rounded horizontal ribs, b, each side of the bottle being thus divided into three panels—namely, the top panel, E, body-panel F, and

base-panel G. The bottle has the usual neck 20 d, with a rib, e, around the upper edge of the same.

I claim—

1. The within-described design for a bottle, said design comprising a rectangular body, A, 25 with contracted top B and bottom D, all substantially as shown and described.

2. The design for a bottle, comprising the body, top, and base sections, A, B, and D, with panels E, F, and G, bounded by rounded ribs 30 a b, as shown and described.

In testimony whereof I have signed my name to this specification in the presence of two subscribing witnesses.

JAMES F. BABCOCK.
